United States Patent Office

Des. 205,000
Patented June 7, 1966

205,000

PITCHER

Roland W. Gregory, Commerce City, Colo.
(7531 Niagara St., Denver, Colo.)

Design application Mar. 9, 1964, Ser. No. 79,163, which
is a continuation of design application Ser. No. 69,443,
Mar. 26, 1962, now Design Patent No. 203,054, dated
Nov. 30, 1965. Divided and this application Oct. 12,
1965, Ser. No. 87,529

Term of patent 14 years

(Cl. D44—21)

FIG. 1.

FIG. 2.

FIG. 1 is a perspective view, taken from the left side,
of a pitcher or the like embodying my new design; and
FIG. 2 is a perspective view, taken from the right side,
of the pitcher of FIG. 1.

This application is a division of my earlier filed application Serial No. D.79,163, of March 9, 1964, now Patent No. D.203,054 of Nov. 30, 1965, which application was continuation of application Serial No. D.69,443 of March 26, 1962, now abandoned.

I claim:

The ornamental design for a pitcher, as shown and described.
